Primary Examiner—Martie Thompson
Attorney, Agent, or Firm—Lawrence I. Wechsler[57] **CLAIM**

The ornamental design for a reflex-correspondence tool, as shown and described.

DESCRIPTION

FIG. 1 is a perspective view of a reflex-correspondence tool showing my new design;

FIG. 2 is a side elevational view, the side opposite being identical thereof;

FIG. 3 is a side elevational view, rotated 90 degrees from the showing of FIG. 2, the side opposite being identical thereto;

FIG. 4 is a top end view; and,

FIG. 5 is a bottom end view thereof.
